(57) **CLAIM**

The ornamental design for a robotic material handling vehicle as shown and described.

DESCRIPTION

FIG. 1 is a front, upper, right isometric view of a robotic material handling vehicle showing the new design.

FIG. 2 is a rear, upper, right isometric view thereof.

FIG. 3 is a front elevational view thereof.

FIG. 4 is a rear elevational view thereof.

FIG. 5 is a right side elevational view thereof.

FIG. 6 is a left side elevational view thereof.

FIG. 7 is a top plan view thereof; and,

FIG. 8 is a bottom plan view thereof.

The broken lines in the figures depict portions of the article which form no part of the claimed design.

1 Claim, 8 Drawing Sheets(56)
